INTERCOMMUNICATION RECEIVING
SWITCH FOR TELEPHONE SYS-
TEMS

Alfred Conhagen, New York, N. Y.

Application September 15, 1948, Serial No. 49,316

7 Claims. (Cl. 179—38)

1

This invention relates to new and useful improvements in telephony, and, more particularly, the invention aims to provide a novel and valuable addition to telephone systems commonly referred to as intercommunicating systems.

Such systems have been highly developed, incorporating a plurality of stations to as large a number as may be desired. Such systems are installed for private use, as in a business organization. At each station is a telephone apparatus incorporating a transmitter and a receiver for permitting cross-communication between one station and another one selected as a calling station. In order to permit a person at any station to select one of the other stations for telephonic hook-up with his station as the calling station, a part of the equipment at each station is a row or bank of selectively operable switches, a selected such switch being closable by depression of an appropriate push button, below termed a call button. When a particular call button is depressed, a communication may be had with the station corresponding to the call button depressed, provided the latter station is not in telephonic hook-up with some third station.

Simultaneously with the establishment of a communication channel between a calling station and another station, a device at the calling station assumes an abnormal disposition, and at the same time all other stations except the calling and the called stations are cut out of said communication channel, and thus each of said other stations is disabled from connecting in with the calling or the called station. In a familiar type of equipment, the call buttons are brown or some other color than white, while the device last referred to is a white button, the said abnormal disposition of which is a projection thereof. The said device is made to have some visually prominent characteristic, with the idea that the person at the calling station, when finished with his telephonic interview with the person at the called station, should have every possible attention-attracting aid to remind him that at the conclusion of such interview he must manually depress said white button, and so clear the system so far as said calling and called stations are concerned.

While the said white button remains projected at any station, that station remains in telephonic hook-up with the station the call of which resulted in automatic projection of said button; and any person at any other station, attempting a telephonic hook-up with either the said calling or called station, would receive a busy signal.

2

It has been found that quite often, due to forgetfulness or to the press of other duties, as at the station of a busy executive, the white button at the calling station is left projected, despite the fact that perhaps even while he is talking with the person at the station called it becomes imperative that he be spoken to over the system by a person at some other station than the called one. Sometimes, in a large factory for instance, the stations are at great distances from each other. Even in that case, the last-named person has no choice but to walk around the premises to locate the station at which the white button is not depressed, with the result that the system is not in use as frequently as it might be, and a person desiring to report to or consult with another has to seek out the latter and speak to him face to face.

Intercommunicating systems are also characterized by the inclusion at each station of a normally open receiving switch, which, according to principles well-known in the art, is so operatively connected with said white button or equivalent that said receiving switch remains closed while the white button remains projected. This operative connection is also such that the means controlled by said white button is also under control of the receiving switch; that is, if the receiving switch were opened, the white button would become depressed, and thus terminate the "busy" condition so far as the calling and called stations are concerned.

According to the present invention, a cross-control means is provided between the different stations for thus acting on the closed receiving switch of a called station, thereby to cause depression of the then projected white button at that station; such means actuatable from any station relative to any other station.

More specifically, according to one embodiment of the invention, an auxiliary group of actuators is provided at each station; which actuators are below called the selector switches. Said switches are manually individually selectively operable, as by push-buttons or otherwise. At each station the number of selector switches provided is equal to the total number of stations less one. At any station, each of the selector switches is wired to a different one of a plurality of electromagnetic instrumentalities, as solenoids, one at each of a different one of the other stations. Each solenoid is normally deenergized, but it is adapted when energized to open the receiving switch at its own station (if then said receiving switch be closed) as the result of the actuation of a selector

switch at another station and appropriate to the station whereat is said solenoid.

Thus, when a person at any station endeavors to call another station and he receives a busy signal, he checks the fact that the system is actually in use by the person at the station sought to be called. If that station is actually in use, the person there will understand what has happened, and, hearing the click of the solenoid at his station, will immediately again depress his white button, thus being able without material interruption to continue his telephonic conversation with whomever he is then holding such conversation. Consequently, the person endeavoring to call him will again hear the busy signal. So he, too, will understand the situation. However, if the person at the sought to be called station has finished use of the system, but has neglected to depress the white button at said station, the now calling station instantly can get through to the station sought to be called.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 shows front elevationally the equipment at each station included in a system of the kind above alluded to, after such an equipment has had added thereto means pursuant to the present invention, said means including a solenoid as its electromagnetic instrumentality relative to the receiving switch of said equipment.

Fig. 2 is a fragmentary section, taken on the line 2—2 of Fig. 1.

Fig. 3 is a diagrammatic view, showing a system having, for example, merely five stations, each served at its receiving switch by a different solenoid; the wiring here being wholly schematic and solely indicative of the standard way in which the stations may be telephonically coupled one with any other.

Fig. 4 is a view illustrating one now favored way of embodying the present invention in connection with the five stations of Fig. 3.

Fig. 5 is a view illustrating a variation, in which the inter-station wiring is simplified over that shown in Fig. 4.

Referring to the drawings more in detail, the typical conventional station equipment illustrated in Fig. 1 includes a cabinet 10 having a widened bottom portion fronted by a panel 11 provided with the aforesaid white button, this indicated at 12, and a bank 14 of four call buttons one for each of the other four stations.

In Fig. 3 (and also in Figs. 4 and 5), the five stations are respectively marked A, B, C, D and E; and in Fig. 3 it will be noted, from an inspection of the arrow-head carrying lines shown, that at the station A a call button b is for establishing communication with the station B, a call button c is for making such a connection with the station C, a call button d is for making such a connection with the station D, and a call button e is for making such a connection with the station E. In the same way, the call buttons a, c, d and e at the station B are for respectively hooking in the stations A, C, D and E; the call buttons a, b, d and e at the station C are for respectively hooking in the stations A, B, D and E; the call buttons a, b, c and e at the station D are for respectively hooking in the stations A, B, C and E; and the call

buttons a, b, c and d at the station E are for respectively hooking in the stations A, B, C and D.

It will further be noted from Fig. 3 that all the call buttons a at the stations B, C, D and E lead to a connection 16 going to the receiving switch 15 of the station A; that all the call buttons b at the stations A, C, D and E lead to a connection 17 going to the receiving switch 15 of the station B; that all the call buttons c at the stations A, B, D and E lead to a connection 18 going to the receiving switch of the station C; that all the call buttons d at the stations A, B, C and E lead to a connection 19 going to the receiving switch of the station D; and that all the call buttons e at the stations A, B, C and D lead to a connection 20 going to the receiving switch of the station E.

Referring now to the arrangement provided by the present invention, the means for closing a then open receiving switch 15 at any station, said means operable for that purpose from any other station, is shown as incorporating a solenoid 21 at each station, and an auxiliary bank or row of buttons 22, each of these for actuation to energize a different one of the solenoids by closing an appropriate one of the aforesaid selector switches. Each solenoid's armature (as shown in Figs. 1 and 2) is operatively coupled to one end of a lever 24 pivoted at 25. The other end of such lever overlies the receiving switch 15. When said switch 15 is closed the part thereof seen in Fig. 2 is projected outwardly from the panel 11 as shown in that view, so that when the lever 24 is arranged as there shown. When, however, the solenoid is energized, the lever is snapped to swing in the direction of the arrow 26, thereby to act on the switch 15 to open the same. As already stated, this results in reopening all communication lines to the station at which the solenoid is energized, accompanied by outward projection of the white button 12 at said station. But, as also already stated, all that is required, immediately to restore the communication line momentarily interrupted by said projection of said white button, is for the person at said station to manually depress said button.

45 Energization of the solenoid 21 at any station may be effected by a person at any one of the other stations. This is done by a depression of any one of the buttons 22 at the latter station; as will be made clear when the wiring arrangements of Figs. 4 and 5 are described.

As the apparatus at each station is illustrated in Figs. 1 and 2, the solenoid 21 is suitably fixedly mounted in a compartment provided within a casing member 27 suitably attached to the standard cabinet 10 opposite one end of the widened bottom portion thereof fronted by the panel 11; a post 28 or the like is suitably fixed in position for pivotally mounting the lever 24 between its ends; and an auxiliary panel 29 for the bank of selector switches 22 is also suitably connected as at 29' to said cabinet. The construction just described is that of an actual satisfactorily operating installation already made, and tested in daily use; but, as will be understood, where a manufacturer of an intercommunicating system incorporates the present invention in standard equipment, a streamlined model is possible, with the solenoid and other working parts inside a single cabinet for all the working parts, as the cabinet 10. As will also be understood, the present invention may be used in connection with a system having as few or as many stations as desired, with, usually, as many selector switches, 70 at each station, as the number of stations less one.

Referring now to Fig. 4, the stations A, B, C, D and E are arranged in diagrammatic-spatial relation substantially as are the same stations in Fig. 3. At each station is also shown a bank of selector switches respectively served by buttons corresponding to the buttons 22 of Fig. 1. At the station A said switches are respectively marked 22^a, 22^b, 22^c and 22^d; at the station B said switches are respectively marked 22^a, 22^b, 22^c and 22^d; at the station C said switches are respectively marked 22^a, 22^b, 22^c and 22^d; at the station D said switches are respectively marked 22^a, 22^b, 22^c and 22^d; and at the station E said switches are respectively marked 22^a, 22^b, 22^c and 22^d.

From each of the selector switches 22^a of the stations B, C, D and E a wire 30, 31, 32 or 33 connects with a main wire 34; and from the latter a wire 35 extends to the solenoid 21 at the station A. From each of the selector switches 22^b of the stations A, C, D and E a wire 36, 37, 38 or 39 connects with a main wire 40; and from the latter a wire 41 extends to the solenoid 21 at the station B. From each of the selector switches 22^c of the stations A, B, D and E a wire 42, 43, 44 or 45 connects with a main wire 46; and from the latter a wire 47 extends to the solenoid 21 at the station C. From each of the selector switches 22^d of the stations A, B, C and E a wire 48, 49, 50 or 51 connects with a main wire 52; and from the latter a wire 53 extends to the solenoid 21 at the station D; and from each of the selector switches 22^a of the stations A, B, C and D a wire 54, 55, 56 or 57 connects with a main wire 58; and from the latter a wire 59 extends to the solenoid 21 at the station E.

From each of the solenoids 21 a wire 60, 61, 62, 63 or 64 extends to a main wire 65; and from all the selector switches at each of the stations A, B, C, D and E is extended a wire 66, 67, 68, 69 or 70, leading to a main wire 71. Said main wires 65 and 71 are connected respectively to the opposite terminals of a current source 72.

Referring to Fig. 5, the stations A, B, C, D and E are shown substantially as in Fig. 3. Here, however, at each station is merely one selector switch 122. The wires 135, 141, 147, 153 and 159 correspond respectively to the wires 35, 41, 47, 53 and 59 in that each one of them extends to a different solenoid 21 for effecting momentary opening of a closed receiving switch 15 at the station with which such solenoid is associated. From each of the selector switches 122 a wire 160, 161, 162, 163 or 164 connects with a main wire 165 also connected with said wires 125, 141, 147, 153 and 159. From each of the selector switches 122 a wire 166, 167, 168, 169 or 170 connects with a main wire 171. From each of the solenoids 21 a wire 172, 173, 174, 175 or 176 extends to a main wire 177. Said main wires 165 and 177 are connected respectively to the opposite terminals of a current source 178.

The modified arrangement just described is one in which the single selector switch 122 at each station is operable to cause momentary energization of the solenoids 21 at all five stations. The principal objection, of course, would be the increased possibility of interrupting more than one conversation. The advantage would lie in the simplicity of construction, and the decrease in the number of wires required.

While I have illustrated and described the preferred embodiments of my invention, it is to be understood that I do not limit myself to the precise constructions herein disclosed and the right

is reserved to all changes and modifications coming within the scope of the invention as defined in the appended claims.

Having thus described my invention, what I claim as new, and desire to secure by United States Letters Patent is:

1. For use in association with an intercommunicating system including means manually operable at any station for establishing telephonic connection with any other station provided the latter station is not already in telephonic connection with some station other than the first-named station and further including means incorporating a device at each station which becomes abnormally positioned there when such station as the calling station has established telephonic connection with a called station and which remains thus abnormally positioned during maintenance of said connection, means whereby said device while thus abnormally positioned is effective to prevent any station other than said calling and called stations from establishing telephonic connection with either of the two last-named stations, an auxiliary system including the combination of a busy-condition-checking means at each station actuatable to restore said device to normal position, and means manually operable from any station for actuating said busy-condition-checking means at another station.
2. For use in association with an intercommunicating system including means manually operable at any station for establishing telephonic connection with any other station provided the latter station is not already in telephonic connection with some station other than the first-named station and further including means incorporating a device at each station which becomes abnormally positioned there when such station as the calling station has established telephonic connection with a called station and which remains thus abnormally positioned during maintenance of said connection, means whereby said device while thus abnormally positioned is effective to prevent any station other than said calling and called stations from establishing telephonic connection with either of the two last-named stations, an auxiliary system including the combination of a busy-condition-checking means at each station actuatable to restore said device to normal position should it then be in abnormal position, and means manually operable from any station for actuating said busy-condition-checking means at another station.
3. For use in association with an intercommunicating system including means manually operable at any station for establishing telephonic connection with any other station provided the latter station is not already in telephonic connection with some station other than the first-named station and further including means incorporating a device at each station which becomes abnormally positioned there when such station as the calling station has established telephonic connection with a called station and which remains thus abnormally positioned during maintenance of said connection, means whereby said device while thus abnormally positioned is effective to prevent any station other than said calling and called stations from establishing telephonic connection with either of the two last-named stations, an auxiliary system including the combination of a busy-condition-checking means at each station actuatable to restore said device to normal position should it then be in abnormal position, and means manually operable from any station for actuating said busy-condition-checking means at another station.

sitioned is effective to prevent any station other than said calling and called stations from establishing telephonic connection with either of the two last-named stations, an auxiliary system including the combination of a busy-condition-checking means at each station actuatable to restore said device to normal position should it then be in abnormal position, and means manually operable from any station for actuating said busy-condition-checking means at another station, said manually operable means at each station having a single actuator in operative connection with and for concurrently operating the several busy-condition-checking means at a plurality of stations other than the station at which said manually operable means is operated.

4. For use in association with an intercommunicating system including means manually operable at any station for establishing telephonic connection with any other station provided the latter station is not already in telephonic connection with some station other than the first-named station and further including means incorporating a device at each station which becomes abnormally positioned there when such station as the calling station has established telephonic connection with a called station and which remains thus abnormally positioned during maintenance of said connection, means whereby said device while thus abnormally positioned is effective to prevent any station other than said calling and called stations from establishing telephonic connection with either of the two last-named stations, an auxiliary system including the combination of a busy-condition-checking means at each station actuatable to restore said device to normal position should it then be in abnormal position, and means manually operable from any station for actuating said busy-condition-checking means at another station, said manually operable means at each station having a single actuator in operative connection with and for concurrently operating the several busy-condition-checking means at all the stations other than the station at which said manually operable means is operated.

5. For use in association with an intercommunicating system including means manually operable at any station for establishing telephonic connection with any other station provided the latter station is not already in telephonic connection with some station other than the first-named station and further including means incorporating a device at each station which becomes abnormally positioned there when such station as the calling station has established telephonic connection with a called station and which remains thus abnormally positioned during maintenance of said connection, means whereby said device while thus abnormally positioned is effective to prevent any station other than said calling and called stations from establishing telephonic connection with either of the two last-named stations, an auxiliary system including the combination of a busy-condition-checking means at each station actuatable to restore said device to normal position should it then be in abnormal position, and means manually operable from any station for actuating said busy-condition-checking means at another station, each of said busy-condition-checking means incorporating an electromagnetic means.

6. For use in association with an intercommunicating system including means manually operable at any station for establishing tele-

phonic connection with any other station provided the latter station is not already in telephonic connection with some station other than the first-named station and further including means incorporating a device at each station which becomes abnormally positioned there when such station as the calling station has established telephonic connection with a called station and which remains thus abnormally positioned during maintenance of said connection, means whereby said device while thus abnormally positioned is effective to prevent any station other than said calling and called stations from establishing telephonic connection with either of the two last-named stations, an auxiliary system including the combination of a busy-condition-checking means at each station actuatable to restore said device to normal position should it then be in abnormal position, and means manually operable from any station for actuating said busy-condition-checking means at another station, each of said busy-condition-checking means incorporating a normally deenergized solenoid.

25 7. For use in association with an intercommunicating system including means manually operable at any station for establishing telephonic connection with any other station provided the latter station is not already in telephonic connection with some station other than the first-named station and further including means incorporating a device at each station which becomes abnormally positioned there when such station as the calling station has established telephonic connection with a called station and which remains thus abnormally positioned during maintenance of said connection, means whereby said device while thus abnormally positioned is effective to prevent any station other than said calling and called stations from establishing telephonic connection with either of the two last-named stations, an auxiliary system including the combination of a busy-condition-checking means at each station actuatable to restore said device to normal position should it then be in abnormal position, and means manually operable from any station for actuating said busy-condition-checking means at another station, said manually operable means at each station including a plurality of selectively manually operable instrumentalities each in operative connection with a busy-condition-checking means at a different one of a plurality of stations other than the station at which said manually operable means is operated, each of said busy-condition-checking means at each station there incorporating a solenoid, and each of said selectively manually operable instrumentalities at each station comprising a selector switch actuatable to cause energization of a solenoid at a different station.
